(57) **CLAIM**

The ornamental design for an electrostatic precipitator air cleaner, as shown and described.

DESCRIPTION

FIG. 1 is a perspective view of an electrostatic precipitator air cleaner showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines and areas within them depict portions of the electrostatic precipitator air cleaner that form no part of the claimed design.

The oblique shading lines in the drawings are included to denote the transparent, translucent, highly polished, or reflective surface quality of surface planes of the humidifier.
